UNITED STATES PATENT OFFICE

CHRISTIAN E. SCHINDLER, OF BARNESVILLE, MINNESOTA

DISPENSING SPOUT

Application filed June 13, 1929. Serial No. 370,572.

This invention relates to a spout for use in dispensing potatoes and the like stored in bins, one of the objects being to provide a spout in the form of a complete unit adapted 5 to be attached to a bin at the point of delivery, said spout including, in its structure, a normally closed valve which can be manipulated readily for permitting the delivery of material in desired quantities.

With the foregoing and other objects in view which will appear as the description proceeds, the invention resides in the combination and arrangement of parts and in the details of construction hereinafter described and claimed, it being understood that changes in the precise embodiment of the invention herein disclosed may be made within the scope of what is claimed, without departing from the spirit of the invention.

In the accompanying drawings the preferred form of the invention has been shown.

In said drawings,

Figure 1 is a top plan view of the spout, a portion of the bin to which it is attached 25 being shown in section.

Figure 2 is a section on line 2—2, Figure 1, one of the positions of the valve, when open, being indicated by broken lines.

Figure 3 is a detail view of an actuating 30 lever for the valve.

Referring to the figures by characters of reference, 1 designates an inclined spout formed of wood, metal, or any other suitable material, having oppositely extending 35 wings 2 at its upper end adapted to be secured by bolts 3 or the like to a wall of a storage bin B. This bin has an outlet O through which material is free to flow into the spout as shown particularly in Figure 2.

The lower or free ends of the sides of the spout are connected by a cross strip 4 and an upper cross strip 5. That portion of the spout nearest the wings 2 is closed at the top 40 as shown at 6 in addition to being closed at the sides and bottom. A space 7 is left between this closed top face and the strip 4 and through this space extends a gate 8 hingedly connected to the top 6 as shown at 9. An arm 10 is extended upwardly from the gate 45 and is connected by a coiled spring 11 to the

strip 5, this spring serving to exert a constant pull on the arm and hold the gate 8 normally closed against the adjacent end of the top 6 and against the bottom of the spout.

Another arm 12 is extended laterally beyond the gate and constitutes a continuation of a transverse reinforcing strip 13 secured to the upper portion of the gate. Arm 12 is adapted to be detachably engaged by the forked end 14 of a lever 15. By placing this lever in engagement with the arm 12 the gate 8 can be swung to open position as indicated by broken lines in Figure 2 and against the action of the spring 11. This will allow a portion of the contents of the bin to gravitate from the spout through an opening 16 between the bottom of the spout and the strip 4 and into a sack or other container provided therefor.

The spout herein described is complete in 70 itself and is adapted to be secured readily to the wall of a bin. Where a bin has a number of outlets, a spout can be attached thereto at each outlet. It is only necessary to have a single lever 15 as this can be carried from place to place and applied to the arm 12 of the gate to be opened.

The entire structure is very simple, compact, and efficient, and is advantageous because it can be erected easily and will keep 75 the spout tightly closed under normal conditions.

What is claimed is:

A delivery spout for attachment to the outlet portion of a storage bin or the like, said spout being inclined downwardly toward one end, means extending from the other end of the spout for attachment to a storage bin or the like, the upper portion of the spout being closed at the top, sides and bottom and the lower portion of said spout being open at the top and bottom but closed across its end, a gate hingedly connected to the top, an arm extending therefrom, a yielding connection between the arm and lower end of the spout for holding the gate normally closed against the top and bottom of the spout, a laterally extending arm carried by the gate, and means detachably engaging the laterally extending arm for swinging the gate against the action 85 of the yielding connection.

of the spring, thereby to open the gate into the open top portion of the spout for deflecting material escaping through the spout into the open bottom portion of said spout.

6 In testimony that I claim the foregoing as my own, I have hereto affixed my signature.

CHRISTIAN E. SCHINDLER.
